US00D943160S

(12) **United States Design Patent** (10) Patent No.: **US D943,160 S**
(45) Date of Patent: ** Feb. 8, 2022

(54) **VAPORIZER DEVICE**(71) Applicant: **JUUL Labs, Inc.**, San Francisco, CA (US)(72) Inventors: **Brandon Cheung**, San Francisco, CA (US); **Carlos A. Dominguez**, San Pablo, CA (US); **Dylan E. Entelis**, Los Angeles, CA (US); **Matthew J. Malone**, Los Angeles, CA (US); **James Monsee**, San Francisco, CA (US); **Zachary T. Scott**, Oakland, CA (US); **John Travis Wettrath**, San Francisco, CA (US)(73) Assignee: **JUUL Labs, Inc.**, San Francisco, CA (US)(**) Term: **15 Years**(21) Appl. No.: **29/713,290**(22) Filed: **Nov. 14, 2019**(51) LOC (13) Cl. **27-02**

(52) U.S. Cl.

USPC **D27/162**

(58) Field of Classification Search

USPC D27/162, 100, 101, 163–165, 172, D27/174–176, 183, 185–194; D24/110, D24/110.5

CPC A24F 47/002; A24F 47/006; A24F 47/008; A61M 15/00; A61M 15/06

See application file for complete search history.

Primary Examiner — Rebecca Tsehay*(74) Attorney, Agent, or Firm* — Mintz, Levin, Cohn, Ferris, Glovsky and Popeo, P.C.(57) **CLAIM**

The ornamental design for a vaporizer device, as shown and described.

DESCRIPTION

FIG. 1 is a top, front, and right side perspective view of a vaporizer device of our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the vaporizer device that form no part of the claimed design.
